UNITED STATES PATENT OFFICE.

ROBERT W. SCOTT, OF LEEDS POINT, NEW JERSEY, ASSIGNOR, BY DIRECT AND MESNE ASSIGNMENTS, TO SCOTT & WILLIAMS, INCORPORATED, OF CAMDEN, NEW JERSEY, A CORPORATION OF NEW JERSEY.

RIBBED KNITTED WEB AND MAKING SAME.

1,087,689.

Specification of Letters Patent. Patented Feb. 17, 1914.

Application filed April 28, 1910. Serial No. 558,225.

To all whom it may concern:

Be it known that I, ROBERT W. SCOTT, a citizen of the United States, residing at Leeds Point, Atlantic county, New Jersey, have invented certain Improvements in Ribbed Knitted Webs and in Making Same, of which the following is a specification.

My invention consists of a novel form of ribbed knitted web and a novel method of producing the same; as fully set forth hereinafter.

In the accompanying drawing Figure 1 is an exaggerated view of a piece of ribbed knitted web in accordance with my invention, and Fig. 2 is a diagram illustrating the disposition of the knitting instrumentalities in a circular machine for producing my improved web.

In Fig. 1 of the drawing, *x* represents the wales of one face of the web and *y* the wales of the other face of the same, the distinctive feature of the web being that the courses of stitches are "staggered," successive stitches of the same yarn being produced in different courses of the web, thus, on reference to Fig. 1, it will be noted that the yarn *m* which produces stitches in courses 1, 3 and 5 of the wales *x*, produces stitches in courses 2, 4 and 6 of the wales *y*, and the yarn *m'* which produces stitches in courses 1, 3 and 5 of the wales *y*, produces stitches in courses 2, 4 and 6 of the wales *x*, the result being that the sinker wales cross each other not only in passing from wale to wale, but in passing from course to course.

In knitting the fabric shown in Fig. 1, I use a machine having two sets of needles A and B, the needles A being mounted in a needle cylinder, needle bed or other needle carrier, and being combined with means whereby they may be operated so as to cause them to knit, and the needles B being mounted in a needle dial, needle bed or other needle carrier and combined with means for causing them to knit in such manner that they will draw stitches in a different direction from that in which the stitches are drawn by the needles A, so as to produce a ribbed fabric, it being understood that my invention is applicable to straight knitting machines or to circular knitting machines, and to machines using either spring beard or latch needles.

Alternating with the needles A are loop

receiving and transferring pins or points *a* 55 and alternating with the needles B are similar pins or points *b*, the points of one carrier being, by preference, in line with the needles of the other carrier, and these points being so actuated that they may be caused 60 either to receive a loop of yarn, or to transfer it to the opposed needle.

In producing the improved web, the yarn *m* is first laid onto the needles A and points *a* and drawn into stitches by said needles A, 65 the other yarn *m'* being at the same time, or subsequently, laid upon the needles B and points *b*, and drawn into stitches by the needles B, after which the points *a* transfer their loops to the needles B, and the points *b* transfer their loops to the needles A, and these loops are drawn into stitches by knocking-over upon them the stitches already 70 upon the needles, these operations being then repeated.

If it is desired to produce one or more uniform courses of stitches between the staggered courses, the transfer points *a* and *b* will be held in a retracted position at the feed or feeds where said uniform courses 80 are being produced, and if it is desired to alternate portions of my improved web with portions of ordinary knitted web, the transfer points will be employed only in those portions of the needle carriers where the 85 improved web is to be produced.

The stitches which are produced from a loop of yarn laid directly upon the needles differ in size from the stitches produced by the transferred loops, thus providing for 90 an alternation of large and small stitches in the wales and courses of the web.

My invention lends itself to the production of fine gage ribbed webs, owing to the fact that the needles in each carrier may be 95 disposed as closely together as in an ordinary machine for knitting plain web, the loop transferring points taking the place of the usual sinkers interposed between the needles in such a machine. In fact, the knitting 100 operations are similar to those which would be performed in knitting two plain webs, the transferring of the loops between successive knitting operations serving to convert two courses of plain knitting into two 105 courses of interlocked rib knitting, my improved fabric resembling the interlocked ribbed fabric of my Letters Patent No.

899,439, dated September 22, 1908, with the additional features of having the sinker wales crossed in passing from course to course and the alternation of large and small stitches in the wales of the web.

The fabric shown in Fig. 1 is what is termed a "one-and-one" rib, the ribs on each face of the web being formed by single needle wales, but it will be evident that other forms of rib may be produced by alternating the transfer points with groups of needles in either carrier, depending upon the character of rib desired.

For the purpose of facilitating production, I prefer to use, in the knitting machine, a plurality of yarn feeds so as to produce successive courses knitted with different yarns, but my improved fabric can be knitted with one and the same yarn by first operating the needles and loop-holding points of one needle carrier to produce thereon a course of stitches with intervening loops, and then permitting the needles and loop holders of this carrier to remain quiescent while knitting a course of stitches with intervening loops by the needles and loop holders of the other carrier, and then transferring the loops of one carrier to the needles of the other carrier and knocking over them the stitches on said needles, and then repeating the operations.

Although in carrying out my invention, I prefer to use transfer points or pins, transferring needles, such for instance as those shown in my Letters Patent 834,763, dated October 30, 1906, may be substituted therefor, if desired.

I claim:

1. A ribbed knitted web having the same number of stitches in each wale and successively formed stitches in a course disposed in one course plane in some of the needle wales and in the plane of an adjoining course in needle wales alternating therewith.
2. A ribbed knitted web having successively formed stitches in a course disposed in one course plane in some of the needle wales and in another course plane in needle wales alternating therewith, and having sinker wales crossed between adjoining needle wales.

3. A ribbed knitted web having wales in which successive stitches are composed of different yarns, each wale having the same number of stitches and successively formed 55 stitches of a course being disposed in one course plane in some of the needle wales and in the plane of an adjoining course in the intervening needle wales.

4. A ribbed knitted web having wales in 60 which successive stitches are composed of different yarns, successively formed stitches of a course being disposed in one course plane in some of the needle wales and in another course plane in the intervening needle 65 wales, and having sinker wales crossing each other between adjoining needle wales.

5. A single ribbed knitted web having the same number of stitches in each wale and successively formed stitches in a course disposed in one course plane in some of the needle wales and in the plane of an adjoining course 70 in needle wales alternating therewith, the stitches of a course which lie in one course plane differing in size from the 75 stitches of the course which lie in the other course plane.

6. A ribbed knitted web having needle wales in which large and small stitches alternate, successively formed stitches of a course 80 occupying one course plane in some of the needle wales and the plane of an adjoining course in intervening needle wales.

7. The mode herein described of producing a ribbed knitted web, said mode consisting in disposing a knitting yarn or yarns to form a course of stitches and intervening loops drawn in one direction, and another course of stitches and intervening loops drawn in another direction, and alternating 85 respectively with the stitches and loops of the first course, and then drawing the loops of one course through the stitches of the other course.

In testimony whereof, I have signed my 95 name to this specification, in the presence of two subscribing witnesses.

ROBERT W. SCOTT
